(57) **CLAIM**

The ornamental design for a ground light, as shown and described.

DESCRIPTION

FIG. 1 is a first perspective view of a ground light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the ground light that form no part of the claimed design. The ground light is shown with symbolic breaks in its length. The appearance of any portion of ground light between the break lines forms no part of the claimed design.

1 Claim, 8 Drawing Sheets
